(57) CLAIM

The ornamental design for a combined organizer and container, as shown and described.

DESCRIPTION

FIG. 1 is a perspective view of a combined organizer and container showing my new design.

FIG. 2 is a back view thereof.

FIG. 3 is a front view thereof.

FIG. 4 is a side view thereof.

FIG. 5 is another side view thereof.

FIG. 6 is a top view thereof.

FIG. 7 is a bottom view thereof; and,

FIG. 8 is an exploded perspective view thereof.

The broken lines in the drawings illustrate portions of the combined organizer and container that form no part of the claimed design.

1 Claim, 8 Drawing Sheets
